CLAIM

The ornamental design for a support belt, as shown and described.

DESCRIPTION

FIG. 1 is a rear perspective view of a support belt showing my new design, the person shown in broken lines is for illustrative purposes only and forms no part of the claimed design;

FIG. 2 is a rear elevational view thereof;

FIG. 3 is a side elevational view thereof;

FIG. 4 is a top plan view thereof;

FIG. 5 is a front elevational view thereof; and,

FIG. 6 is a bottom plan view thereof.

The crosshatch shading in FIGS. 1, 2 and 5 is understood to repeat throughout the indicated area.
